CAR DOOR FASTENING

Dibrell P. Hynes, Chicago, Ill., assignor to Chicago Forging & Manufacturing Co., Chicago, Ill., a corporation of Illinois

Application August 15, 1935, Serial No. 36,258

1 Claim. (Cl. 292—52)

My invention relates to improvements in closures and has for one purpose the provision of closure means whereby a door may be moved into closed position prior to the actuation of the locking means intended to hold it in closed position. One application of my invention is to rear closures for automobiles, but it will be understood that a wide variety of other applications may be made of the invention. One object is the provision of means for permitting the closure of doors having yielding packings or pads or buffers. Another object is the provision of means for moving a door into closed position prior to the movement of a closing latch along an axis or in a plane generally parallel with the plane of the door itself. Other objects will appear from time to time in the course of the specification and claim.

I illustrate my invention more or less diagrammatically in the accompanying drawings, wherein—

Figure 1 is a side elevation of a car, with parts broken away, showing the door in open position;

Figure 2 is an edge view of the door shown in Figure 1;

Figure 3 is a plan view of the door in locked position;

Figure 4 is a section on the line 4—4 of Figure 2, showing the locking unit separately, the parts being shown in unlocked position;

Figure 5 is a section similar to Figure 4, showing the locking unit in place on the door, the parts being shown in locked position;

Figure 6 is a section similar to Figure 4 on an enlarged scale;

Figure 7 is a section on the line 7—7 of Figure 5;

Figure 8 is a section on the line 8—8 of Figure 5;

Figure 9 is a section on the line 9—9 of Figure 5;

Figure 10 is a top plan of a center locking bolt or tongue;

Figure 11 is a section on the line 11—11 of Figure 10; and

Figures 12 and 13 are diagrammatic views, illustrating the action of the locking levers and locking bolt.

Like parts are indicated by like symbols throughout the specification and drawings.

Referring to the drawings, 1 generally indicates the body of an automobile, and 2 the rear car door hinged as at 3 by any suitable offset supports 4. 5 indicates rubber padding around the door closure. Such padding or packing means,

preferably yielding or elastic, may be applied to the door frame or to the door or to both as shown, for example, in Figure 9. Referring to Figure 9, the door is shown as being bounded by a frame which includes an inwardly turned flange 6, a flange 7, and a lip 8, the yielding packing or padding 5 being fitted into the space bounded by the members 6, 7 and 8. Any suitable additional reinforcement may be employed shown in Figure 9 as an angle 9, bolted in position as by the bolt 10 and adapted to serve as abutment means for the door positioning locking means below described.

The door, generally indicated as 2 in Figure 1, includes preferably a single outer panel or surface member 20. The upper portion of the door, the body of the door proper may be formed in any suitable way, but I illustrate an inner door portion 21 provided with the flange 22 and a lip or angle 23 abutting against the inner face of the panel 20 at a point somewhat short of the lower edge of the door. The parts may be spot welded or otherwise secured together. In order to provide a convenient positioning locking unit for the door which is readily applicable to the door before or during the passage of the automobile down the assembly line in the course of its manufacture, I employ a species of panel or housing generally indicated as 25 which includes a flange 26 opposed to the flange 22, as shown in Figure 7, an inclined portion 27, and an additional portion 28 generally parallel with the door panel 20, and a flange 29 extending from the portion 28 to the inner face of the door panel 20, to which it may be secured as shown in Figure 7. The member 28 is apertured as at 32 in line with the locking structure below described. The housing is provided with end walls 31 as shown, for example, in Figure 4. Extending from end to end of the housing so formed and generally parallel with the member 28 is a bracket plate 33 which is formed at its ends with upturned flanges 34 which may be riveted or otherwise secured to the ends 31 of the panel housing. This plate or support 33 has at one edge the upstanding flange 35 which is secured to the front edge of the door which is formed at that point by the member 29. This structure will be clear from Figure 7.

Mounted for rotation in the door panel 20 and the bracket or support 33 is the handle 40 which is provided with an enlargement or boss 41 abutting against the forward face of the panel 20, and a reduced cylindrical portion 42 which extends through receiving apertures in the members 20 and 33 which apertures may be bounded by 55

upset bearings 44, 45 respectively. A further reduced portion 46 is screwthreaded to receive the nut 47 which, through the intermediary of the washer 48, keeps the locking and actuating handle 40 in position. The locking lever 50 itself is shown, for example, in Figure 10 and is well illustrated also in Figures 7 and 8. It has an upset portion 51 with an irregular aperture 52 therethrough. The portion 46 may be formed, 10 in cross section, to conform to the aperture 52, whereby to prevent relative rotation of the members 46 and 50. The upset portion 51 which has a circular or cylindrical outer face seats in a circular aperture 54 in the bracket 53, which 15 bracket is secured as by a bolt or screw 53a to the supporting member 33, as shown, for example, in Figure 8. It will be seen, therefore, that while the nut 47 holds the parts together, when the nut 47 is unscrewed, as it can be through the 20 aperture 32, only the handle 40 and its integrally associated parts can be removed and all the remaining parts are held in position. It will be understood, however, that when the parts are 25 assembled a rotation of the handle 40 will rotate also the locking lever 50.

Extending from the locking lever 50 is a pin 55 which has rotatably mounted upon it a stirrup 56. 57 is a rock shaft rotatably mounted upon the member 33. It may, for example, have 30 integral bearing ears struck up at various points therealong as at 58 or other ears 59 which are mounted upon the plate or support 33. Adjacent the ends of the rock shaft are offset portions 60 the purpose of which will later appear. An 35 intermediate offset 61 passes between the stirrup 56 and the pin 55. It will be understood that when the handle 40 is rotated the corresponding rotation of the locking lever 50 will cause the rock shaft to rotate. This rotation will cause 40 the offset portions 60 to move from the inactive dotted line position of Figure 9 to the active or locking full line position of Figure 9. In other words, a rotation of the handle 40 is effective to 45 force the fingers in such position that they draw the door inwardly against the door frame and press the rubber buffers or packings as shown in Figure 9. When the door has been moved into closed position then, and only then, is it possible for the locking lever 50 to move into full locking position. It is provided with a projecting tongue or extension 65 which is offset or beveled as at 66, to permit it to ride over the opposed locking abutment as shown at 67 in Figure 7. 68, 69 are stops for limiting the movement of the 50 locking lever. When it is in unlocked position it engages the stop 68. When it is in locked position it engaged the stop 69, referring to the position of the stops, for example, in Figures 4 and 5. It will be understood that the stops are so 55 located that when the locking lever 50 is moved 60

into locking position, it is held positively in locking position by the elasticity of the rock shaft 57. In other words, the pin 55 moves past center. Apertures 76—76 are provided for the offset levers 60 of the rock shaft and the tongue 65 of the locking lever 50 projects through the aperture 77 in the flange 29 when in locked position.

In the operation of the device, the lead of the members 60 over the locking lever 50 is such that they have exerted a sufficient pull to draw the door practically into full locking position, before the locking lever 50 rides over the abutment 67 into locking position.

In the application of the device to an automobile it will be understood that the top panel 20 of the door is unbroken except by the aperture through which the handle portion 42 passes. The door structure proper, which is compound, as shown for example in Figure 7, is provided 20 with a recess, concealed from the outside, but bounded by the walls 22 and 75, which side walls 75 are shown, for example, in Figure 5. Into this recess the panel or housing structure above described drops as a unit and all that is then necessary, apart from whatever molding or spot welding may be necessary, is to insert the handle in position, place the washer 48 in position and run up the lock nut 47.

It will be realized that whereas I have described and shown a practical and operative device, nevertheless many changes may be made in size, shape, number and disposition of parts without departing from the spirit of my invention. I therefore wish my description and showing to 35 be taken as in a broad sense illustrative and diagrammatic rather than as limiting me to my specific showing.

I claim:

In closing and locking means for a door having a packing adapted to be compressed upon closing of the door, a rock shaft rotatably positioned on said door, levers associated with said rock shaft and adapted, in response to rotation of said shaft, to draw said door toward the closed position, an additional locking means, and means for actuating it, adapted to lock said door in position after it has been moved a predetermined distance toward the closing position in response to rotation of said rock shaft, unitary handle means adapted, in response to a predetermined movement of said handle, first to rotate said shaft and thereby draw the door toward closed position to initially compress the packing, and thereafter, after a predetermined closing movement of the door, to close said locking means, said locking means including a locking lever mounted to move in unison with said handle.

DIBRELL P. HYNES.

60.
